(57) **CLAIM**

The ornamental design for a tote bag with configurable corners, as shown and described.

DESCRIPTION

FIG. 1 is a perspective view of a tote bag with configurable corners showing the new design, in the open expanded configuration with the corner pockets in the retracted configuration;

FIG. 2 is a top plan view of the tote bag with configurable corners in FIG. 1;

FIG. 3 is a perspective view of the tote bag with configurable corners in the open expanded configuration with the corner pockets in the extended configuration;

FIG. 4 is a top plan view of the tote bag with configurable corners in FIG. 2;

FIG. 5 is a perspective view of the tote bag with configurable corners in the closed configuration with the drawstring cinched;

FIG. 6 is a top plan view of the tote bag with configurable corners in FIG. 5;

FIG. 7 is a perspective view of the tote bag with configurable corners with the drawstring not cinched and folded in to expose the interior of the bag;

FIG. 8 is a top plan view of the tote bag with configurable corners in FIG. 7;

FIG. 9 is a first side elevational view of the tote bag with configurable corners of FIGS. 1 and 3;

FIG. 10 is a second side elevational view of the tote bag with configurable corners of FIGS. 1 and 3;

FIG. 11 is a first end elevational view of the tote bag with configurable corners of FIGS. 1 and 3;

FIG. 12 is a second end elevational view of the tote bag with configurable corners of FIGS. 1 and 3;

FIG. 13 is a bottom plan view of the tote bag with configurable corners of FIGS. 1 and 3;

(Continued)

FIG. 14 is a first side elevational view of the tote bag with configurable corners of FIGS. 5 and 7;
 FIG. 15 is a second side elevational view of the tote bag with configurable corners of FIGS. 5 and 7;
 FIG. 16 is a first end elevational view of the tote bag with configurable corners of FIGS. 5 and 7;
 FIG. 17 is a second end elevational view of the tote bag with configurable corners of FIGS. 5 and 7;
 FIG. 18 is a bottom plan view of the tote bag with configurable corners of FIGS. 5 and 7, except with the flaccid drawstrings overhanging the outside of the tote bag; and,
 FIG. 19 is a side elevational view of the tote bag with configurable corners showing the drawstring tucked.
 The stitching is not part of the claimed invention.
 The broken lines depict stitching that forms no part of the claimed design.

1 Claim, 11 Drawing Sheets
